AUTOMATIC CONTOUR-STITCHING
MACHINE

Saul Schiller, Brooklyn, N. Y.

Application October 29, 1946, Serial No. 706,456

15 Claims. (Cl. 112—102)

1

The present invention relates in general to sewing machines and more particularly to an improved sewing machine of the type designed to stitch articles of fabric or other material in a variety of directions and in accordance with a predetermined pattern.

An object of the invention is to provide improved means for supporting and moving the article to be stitched.

A further object is to provide improved article-supporting means which is mounted for universal movement in a horizontal plane and driven by drive-means which is so arranged with respect to the supporting-means that all force-vectors applied thereon by said drive-means are in symmetry with respect to the longitudinal and transverse axes of said supporting-means.

A still further object is to provide improved mounting-means for the article-supporting means such that the rack-plate which controls the movement of the supporting-means is suspended above and in cooperative engagement with the drive-means.

A still further object is to provide a sewing machine of the type having an oscillating shuttle shaft with drive-means for transmitting intermittent motion to the article-supporting means.

A still further object is to provide improved mechanism for resetting the article-supporting means at the end of a sewing cycle, the supporting-means resetting mechanism being cooperatively associated with the article-clamping means so as to be actuated simultaneously therewith when the elements of an article are assembled and clamped to the supporting-means.

A still further object is to provide improved clamping-means for securing the article to the supporting-means.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a side elevation of the improved sewing machine of this invention, a part of the view being broken away to show a section of the base of the machine;

Fig. 2 is a top plan view partly in section of the machine shown in Fig. 1;

Fig. 3 is a bottom plan view of the machine showing the intermittent drive-means and the supporting-means resetting mechanism;

2

Fig. 4 is an end elevation of the left-hand end of the machine as seen in Fig. 1, showing the improved ratchet-means for locking the article-clamping means in clamping position;

5 Fig. 5 is a sectional elevation of the article-clamps on line 5—5 of Fig. 2;

Fig. 6 is a sectional elevation on line 6—6 of Fig. 2 showing the pinion-member for driving the rack-plate of the article-supporting means, and the friction-drive bands and brake-band cooperatively associated with the pinion-member; and

10 Fig. 7 is a fragmentary end elevation on line 7—7 of Fig. 2 of the latch of the automatic stop-means.

15 In carrying out the present invention, a sewing machine is used, indicated generally at 10, having a conventional reciprocating needle 11 which is actuated by a substantially-horizontally-disposed drive-shaft 12. The latter carries an idle-pulley 13 freely mounted on its outer end which is adapted to be driven by a belt from a power source not shown. A conventional belt-shifter (not shown) is adapted to transfer the drive from

20 the idle-pulley 13 to a drive-pulley 14 which is keyed to the shaft 12. The drive-pulley 14 is provided with a hub-portion 15 having a radially-projecting lug 16 which is adapted to be engaged by the upper end 17 of a pivoted stop-lever 18,

25 the latter being mounted on a transverse pivot-pin 19 so as to swing in a vertical plane clockwise and counterclockwise, as viewed in Fig. 1. The stop-lever 18 is biased by means of a flat leaf-spring 20 to swing clockwise or outwardly so that

30 its upper end 17 will engage the lug 16 of the drive-pulley and stop rotation of the needle-shaft 12. The stop-lever 18 is adapted to be held in its retracted or inoperative position, as shown, by means of a bell-crank lever 21 which is pivoted

35 as at 22 to the frame of the machine so as to rotate in a vertical plane at substantially right angles to the plane of rotation of the stop-lever 18, the lever 21 having a short-arm 23 at its lower end arranged normally to engage the lower end

40 of the pivoted spring-biased stop-lever 18. The long upper-arm 24 of the pivoted bell-crank lever 21 is provided with a horizontally-extending reach 240 which is adapted normally to be supported on the upper edge of the rearwardly-extending arm 25 of a lever 26 pivoted as at 260

45 to the sewing machine head and extending substantially parallel to the longitudinal axis of its base 27. The lever 26 is biased to swing in a counterclockwise direction, as seen in Fig. 1, by means 50 of a coil-spring 28 which is secured at one end

to the rear-arm 25 of the lever and at its opposite end to the head of the machine, the lever 26 being adapted to be held in its normal substantially-horizontal position by suitable latch-means, indicated generally at 28, mounted on the forward-arm 30 of the lever.

Referring to Figs. 2 and 7, the latch-means 29 comprises a knuckle 31 pivoted at the end of the forward-arm 30 so as to swing in a substantially-horizontal plane, and provided with a finger 32 extending normally in a substantially-horizontal plane at right angles to the lever-arm 30. The outer end of the finger 32 is provided with a prop 33 which is pivoted at its upper end to the outer end of the finger 32 and adapted to extend downwardly so as to engage on the outer edge of the base 21 of the sewing machine, as shown in Fig. 7. The prop 33 is resiliently held in a substantially-vertical position by a spring 34 which is secured at one end to the outer extremity of the finger 32 and at its opposite end to the upwardly-extending end of the pivoted prop 33, the force of the spring 34 holding the upper end of the prop 33 in engagement with a stop-pin 35 projecting from the outer end of the finger 32. The prop 33 is free, however, to pivot in a clockwise direction, for the purpose hereinafter described.

Referring to Fig. 2, the opposite end of the finger 32 is engaged by a coil-spring 36 which, in turn, is connected at its opposite end to the arm 30 of the lever 26 so as to resiliently hold the finger 32 in a normal position substantially at right angles to the lever 26, a suitable stop-collar 37 being secured to the forward end 30 of the lever immediately adjacent the pivoted knuckle 31 to prevent the latter, including the spring-biased finger, from swinging in a counter-clockwise direction.

From the foregoing description it will be clear that as long as the prop 33 of the pivoted finger 32 is engaged on the outer edge of the base 27, the lever 26 will be held in a substantially-horizontal position, as viewed in Fig. 1, but that whenever the prop 33 is displaced from the outer edge of the base, the lever 26 will be rotated about its pivot 260 by the force of the spring 28 and thereby elevate its rearwardly-extending arm 25 against the underside of the reach 240 of the long-arm 24 of the bell-crank lever 21. When this occurs, the short-arm 23 of the bell-crank lever 21 will swing counterclockwise out of engagement with the lower end of the spring-biased stop-lever 18, as a consequence of which the latter will swing outwardly or clockwise, as viewed in Fig. 1, and thrust its upper end 17 into the path of the lug 16 of the drive-pulley 14, thus immediately stopping the rotation of the needle-shaft 12, the drive-belt being simultaneously shifted to the idle-pulley 13.

The needle-shaft 12 is provided adjacent its rear end with a crank 38 and connecting-rod 39, the lower end of the latter being pivotally secured to the short-arm 40 of a bell-crank lever 41 pivotally supported on the end of a stud-shaft 42 mounted on the underside of the base 27 of the machine. The long-arm 43 of the bell-crank lever 41 is slotted longitudinally and adapted to receive in its slot a roller 44 which is carried on the end of a crank-arm 45. The latter is secured to the rear end of a shuttle-shaft 46 which runs substantially coaxial with the longitudinal axis of the base of the machine, being supported at its opposite ends in suitable bearings on the underside thereof. The linkage connecting the rotating needle-shaft 12 and the bobbin-shaft 46

will be recognized as a well-known means for converting continuous rotary motion into oscillatory motion, which is the characteristic motion of the shuttle-shaft 46.

- 5 Drilled in the base 27 of the machine, substantially intermediate its opposite ends and on the longitudinal axis thereof, is an aperture 47 provided with a cylindrical bushing 48 adapted to receive a pinion-member, indicated generally at 49. The latter comprises a hub 50 rotatably mounted in the bushing 48 and provided at its lower end with an integral flange comprising a relatively-thin disk 51, the diameter of which is several times greater than the diameter of the hub 50. As shown in Fig. 1, the pinion-disk 51 is located between the underside of the base 27 of the machine, and the oscillating shuttle-shaft 46 being held in operative position by means of a pair of bars 137 (see Fig. 3) secured to the underside of the base 27 and traversing opposite edges of the pinion-disk 51. The upper end of the hub 50 extends above the top surface of the base of the machine and is provided around its periphery with an annular series of pinion-teeth 52. Extending upwardly above the plane of the pinion-teeth 52 and coaxial with the longitudinal axis of the hub 50, is a cylindrical cam guide-pin 53, the latter being preferably formed as an integral extension of the hub. The pinion-teeth 52 and cam guide-pin 53 are adapted to cooperatively engage with the rack-teeth and cam-groove respectively of the article-supporting means for operating the latter in the manner and for the purpose hereinafter described.

35 Referring to Figs. 3 and 6, the pinion-member 49 is adapted to be rotated intermittently, and to this end a friction drive-band 54 is provided which circumscribes the periphery of the pinion-disk 51 adjacent the lower edge thereof, the oppositely-disposed ends of the friction drive-band 54 being provided with substantially-rectangular flanges 55 and 56 respectively. Pivotal secured to the flange 55 is a lever of the second class, indicated generally at 57, comprising a horizontally-slotted web-portion 58 formed integrally at the left-hand end of the arm of the lever 57 and at substantially right angles thereto, as seen in Fig. 3. The slotted web is adapted to be secured to the flange 55 of the friction drive-band 54, and to this end the flange 55 is inserted into the slot of the web 58 and pivotally secured therein by a fulcrum-pin 59. Pivotal secured in the slot of the web 58, intermediate its fulcrum-pin 59 and the arm of the lever 57, is one end of a link 60, the opposite end of which is provided with an elbow 61 bent at an angle of substantially 45° thereto and slotted horizontally to receive the flange 56 of the friction drive-band 54, the flange 56 being secured in the slot of the elbow 61 by a pivot-pin 62, as shown clearly in Fig. 3. The end 63 of the arm of the lever 57 is bent at substantially right angles thereto in a direction opposite to but in the horizontal plane of the web-portion 58, and secured to the end 63 of the lever-arm is one end of a chain 64 which is adapted to encircle the perimeter of a semicircular disk 65 secured to the shuttle-shaft 46, the opposite end of the chain 64 being secured to the perimeter of the semicircular disk 65 by suitable fastening-means, as shown in Fig. 3. Suitably secured to the outer edge of the flange 56 of the friction drive-band by a screw 660 is one end of a draw-wire 66 which partially encircles the periphery of the drive-band 54. The wire 66 is secured at its opposite end to one end of a coll-

spring 67, the opposite end of the latter being, in turn, anchored to a post in the underside of the base of the sewing machine.

In accordance with the foregoing construction, it will be evident that as the shuttle-shaft oscillates, the chain 64 will be drawn around the semicircular disk 65 during each half-revolution of the shaft in a clockwise direction, as viewed in Fig. 3, and thus pivot the lever 57 in a counterclockwise direction about its fulcrum-pin 59. The counterclockwise movement of the lever 57 will initially pull the link 60 to the left so as to draw the flanged end 56 of the friction drive-band 54 closer to the oppositely-disposed end 55 of the drive-band. In this manner, the friction drive-band 54 is tightened around the periphery of the pinion disk 51 with sufficient frictional force to rotate the disk during the subsequent movement of the lever 57. The angle of rotation of the pinion-disk 51 is a function of the radius of the semicircular disk 65 and the distance between the center of the pinion-disk 51 and the semicircular disk 65 of the shuttle-shaft. In the present embodiment, these dimensions are so selected that the pinion-disk 51 will be rotated through an angle of substantially 10° with each movement of the lever 57 in a counterclockwise direction. When the direction of rotation of the oscillating bobbin-shaft 46 is reversed, the chain 64 releases the lever 57, whereupon the friction grip of the drive-band 54 is released, the lever 57 and band 54 being thereupon drawn back by the force of the coil-spring 67 pulling on the draw-wire 66. The retraction of the loosened drive-band 54 is limited by an adjustable stop 68 against which the edge of the flange 56 of the drive-band 54 is adapted to abut when in its normal position.

In order that the pinion-member 49 will remain stationary while the friction drive-band 54 is being retracted to its normal position, a brake-band 69 is provided which encircles the periphery of the pinion-disk 51 adjacent the upper edge thereof, as shown in Fig. 6. Referring again to Fig. 3, the oppositely-disposed ends of the brake-band are provided with suitable flanges 70 and 71 respectively, the edge of the flange 70 being adapted to abut a fixed post 72 projecting from the base of the machine. The edge of the flange 71 of the brake-band 69 is adapted to be engaged by the arm 73 of a spring-loaded brake-lever 74 pivoted at 75 to the base of the machine, the arm 73 being normally held in engagement with the edge of the flange 71 of the brake-band by the force of a coil-spring 76, one end of which is secured to the lever-arm 73, the opposite end being suitably anchored to the base of the machine. The spring-loaded arm 73 of the brake-lever 74 is thus adapted to force the end 71 of the brake-band toward the fixed end 70 thereof so as to tighten the brake-band around the periphery of the pinion-disk 51. The friction grip of the brake-band 69 around the pinion-disk 51 is, however, somewhat less than the friction grip of the drive-band 54, as a consequence of which the friction drive-band 54 is enabled to rotate the pinion-member 49 in one direction. When the drive-band 54 is retracted, the brake-band will hold the pinion-member stationary, the resulting motion of the pinion-member being an intermittent rotary motion in one direction.

In accordance with a further object of the invention, suitable means are provided for reversing the rotation of the pinion-member in order

to reset the article-supporting means at the end of each sewing cycle. This is done in order to effect a short length of superposed stitching on the article for tying together the loose ends of the threads. To this end, a second friction drive-band 77 is mounted on the periphery of the pinion-disk 51, the oppositely-disposed ends of the drive-band 77 being provided with outwardly-projecting flanges 78 and 79 respectively. The flange 78 is pivotally secured in the slotted end of a horizontally-slotted lever 80, at the outer end of which is secured one end of a cord or chain 81 for operating the second friction drive-band 77, as hereinafter described. Intermediate the outer and inner ends of the lever 80 is a pivot-pin 82 which pivotally connects one end of a right-angle lever 83 in the slot of the lever 80, the opposite end of the right-angle lever 83 being slotted horizontally to receive the flange 79 of the second drive-band to which it is pivotally secured. The lever 80 is biased by a coil-spring 84 which is secured at one end to the pivot-pin 82 of the lever 80, its opposite end being suitably anchored to the base of the machine. The force of the coil-spring 84 normally pulls the lever 80 in a counterclockwise direction (See, Fig. 3) so as to spread apart the oppositely-disposed ends of the friction drive-band 77 which is positively held from rotating by a pin 790 in engagement with the flange 79. The second drive-band 77 thus does not normally grip the pinion-disk 51. However, by pulling on the cord 81 so as to swing the lever 80 in a clockwise direction, the second friction drive-band 77 will be tightened around the periphery of the pinion-disk 51 sufficiently to frictionally rotate the latter in a clockwise direction counter to the normal direction of rotation of the pinion-member. In this connection, the cord 81 is shown bent around a post 85 carried at the extremity of an extension 86 of the brake-lever 74 so that when the cord 81 is pulled, a force component of the latter acts on the post 85 to swing the arm 73 of the brake-lever 74 out of engagement with the edge of the adjacent flange 71 of the brake-band 69, thus releasing the brake-band from frictional engagement with the pinion-disk 51. Consequently, the pinion-disk 51 is freed and is thereupon rotated in a clockwise direction by the second drive-band, the corresponding counter rotation of the pinion-member 49 being for the purpose of resetting the article-supporting means.

The article-supporting means is mounted on the top side of the base of the machine and comprises a carriage, indicated generally at 87, to which is secured the article-holding plate, indicated generally at 88, the carriage and plate being suitably mounted for universal movement in a horizontal plane, as hereinafter described. Referring to Figs. 1 and 2, the carriage 87 comprises a pair of spaced parallel guide-rods 89 adapted to extend across the base of the machine at right angles to the longitudinal axis thereof, the rods being slidably mounted at their opposite ends in bearing-blocks 90 each of which comprises an L-shaped bracket 91 secured to the top side of the base of the machine and extending laterally from opposite sides thereof, as shown in Fig. 2. Extending transversely across the guide-rods 89 in spaced parallel relationship and between the bearing-blocks 90 thereof, are a pair of bearing-brackets 92 rigidly secured to the said guide-rods, as shown in Fig. 1, and provided with bearing-hangers 93 bent downwardly

at substantially right angles to the brackets. Each hanger 93 is provided with a bearing-aperture 94, the longitudinal axes of the bearing-apertures 94 of each clamp being in axial alignment and substantially parallel to the longitudinal axis of the base. Supported in the axially-aligned bearing-apertures 94 of the clamps 92, are a second pair of spaced parallel carriage guide-rods 95, the latter being slidably mounted at their opposite ends in the bearing-apertures of the brackets. The carriage guide-rods 95 are adapted, in turn, to support a substantially-rectangular rack-plate 96. To this end, a carriage-clamp 97 is secured at its opposite ends to the corresponding guide-rods 95 at substantially right angles thereto and between the bearing-hangers 93 thereof. As shown in Fig. 2, the rack-plate 96 is secured to the underside of the transverse carriage-clamp 97 by screws 98 or equivalent fastening-means, the longitudinal axis of the rack-plate being midway between the guide-rods 95 and parallel to the longitudinal axis of the machine base 27. In accordance with this construction, the rack-plate is supported by the carriage guide-rods for substantially-universal movement in a horizontal plane which is parallel to the plane of the base 27 and between the latter and the horizontal plane of the carriage guide-rods 89.

The rack-plate 96 is provided on its underside with a cam-groove 99 having the configuration of the pattern to be sewn on the article or work-piece, the cam-groove being substantially symmetrical with respect to the longitudinal axis of the rack-plate. Provided around the periphery of the cam-groove 99 and at a uniform distance therefrom, are a plurality of downwardly-projecting sequentially-spaced pins or rack-teeth 100 which follow the configuration of the cam-groove 99. The latter and the rack-teeth 100 are adapted to be engaged by the cam guide-pin 53 and the teeth 52 respectively of the pinion-member 49, so that when the latter is rotated intermittently, as described above, the rack-plate 96 will be intermittently moved through a path corresponding to the configuration of the cam-groove 99. It will be noted that the spaced parallel guide-rods 89 of the carriage are mounted substantially symmetrically with respect to the pinion-member 49, i. e., the guide-rods 89 are at substantially-equal distances on opposite sides of the center of the pinion-member. Moreover, the rack-plate 96 is supported by the carriage substantially symmetrically with respect to the guide-rods 95. In accordance with this construction, all force vectors acting on the rack-plate 96 to move the latter substantially transverse to the longitudinal axis of the base 27 of the machine, act substantially symmetrically with respect to the spaced parallel guide-rods 89, while all force vectors acting longitudinally of the base 27 act substantially symmetrically with respect to the spaced parallel guide-rods 95. Consequently, if there are any force movements tending to bind the respective pairs of carriage guide-rods in their bearings, these will be held to a minimum.

Bolted or otherwise secured to the forward end of the rack-plate 96 of the carriage 87, is the article-holding plate 88 which is substantially rectangular, its longitudinal axis being in axial alignment with the longitudinal axis of the rack-plate 96. An aperture 101 is formed in the article-holding plate 88 which, in the present embodiment, is substantially circular and in-

cludes an elongated radially-extending groove 102 adjacent the forward edge of the work-piece holding-plate 88 and coincident with the longitudinal axis thereof. Secured to the underside 5 of the work-piece holding-plate is a runner-plate 103 (see Fig. 5) which is adapted to slidably engage on the top surface of the base 27 of the machine so as to support the end of the work-piece holding-plate thereon. The runner-plate 103 has an aperture 104 corresponding substantially to the configuration of the cam-groove 99 of the rack-plate and concentric with and considerably smaller than the aperture 101 of the work-holding plate 88, the edge of the aperture 104 being adapted to constitute a relatively-narrow ledge 105 on which the work-piece may be supported during the stitching operation. Located at suitably-spaced points along the ledge 105 and back from the edge of the aperture 104, 10 are a plurality of upwardly-projecting work-piece positioning-prongs 106 adapted to facilitate the assembly of the elements of the work-piece on the supporting-ledge 105 of the runner-plate 103. The particular article to be sewn on the present 15 machine is a man's garter comprising a pair of superposed hexagonal pads adapted to have two elastic bands stitched therebetween in angular relationship at one end thereof, and a stocking-supporter stitched at its opposite end. Hence, 20 the configuration of the cam-groove of the rack-plate and the aperture 104 in the runner-plate is substantially hexagonal, so that in stitching the pads together, the line of stitching will follow a substantially-hexagonal path around the outer 25 edges of the pads. In order to temporarily support the elastic bands and the stocking-supporter in the apertured holding-plate 88, the aperture 101 thereof is provided with grooves 1010 for the elastic bands of the garter, the stocking-supporter of the garter being adapted to lie in the 30 groove 102.

Suitable means are provided for clamping the pads, elastic bands and stocking-supporter in assembled relationship on the ledge 105 of the runner-plate 103. Referring to Figs. 2, 4 and 5, the work-piece clamping-means comprises a pair of semi-circular frame-members 107, each being provided intermediate its opposite ends with an integral outwardly-projecting arm 108. The 35 outer ends of the arms 108 are secured to the respective rear ends of suitable shafts 109 at substantially right angles thereto, the shafts being rotatably mounted in axially-aligned bearings 110 on opposite sides of the work-holding plate 88. The shafts 109 are held from moving longitudinally in the bearings 110 by means of suitable thrust-collars 111 secured to the forward ends of the respective shafts 109, the outer extremities of which are provided with grooved pulleys 112 40 each secured to its respective shaft by a screw or other fastening-means. Secured to each pulley 112 is a bracket 113 to which is secured one end of a coil-spring 114, the latter extending from the bracket 113 of one pulley around the 45 outer periphery thereof, across the front end of the work-holding plate and around the outer periphery of the other pulley to which it is secured by its corresponding bracket 113. The shafts 109 are thus spring-biased to rotate in opposite directions, the shaft at the right-hand side of the work-piece holding-plate 88 being rotatable clockwise and the shaft at the left-hand side of the plate being rotatable counterclockwise. 50 55 60 65 70 75 In accordance with this construction, the frame-

members 107 of the respective shafts are normally urged to swing upwardly and outwardly away from the work-piece retaining-aperture 101 of the work-piece holder 88. Referring again to Figs. 2 and 5, the frame-members 107 are equipped with suitable resilient members for engaging the elements of the work-piece when the latter are supported on the ledge 105 within the aperture 101 of the holding-plate. These resilient members constitute looped wires 115, each wire being substantially-U-shaped and secured at its opposite ends by screws or other means to its respective frame-members 107, the length of each wire-loop corresponding to the length of that side of the edge of the aperture 104 of the runner plate 103 opposite which the loop is secured. As shown in Fig. 5, each loop 115 is bent downwardly at substantially right angles to its point of attachment to its respective frame-member so as to positively engage the assembled elements of the work-piece.

In order to positively hold the resilient wire-loops 115 of the frame-members in engagement with the elements of the work-piece during the sewing cycle, suitable ratchet-means is provided, indicated generally at 116. Referring to Fig. 4, the ratchet-means 116 comprises a pulley 117 supported to rotate in a vertical plane by a pin 118 extending forwardly from the front face of a stanchion 119 secured to the forward end of the work-piece holding-plate 88. The pulley 117 is supported substantially intermediate the pulleys 112 and is provided at substantially-diametrical-ly-opposite points on its outer face with two outwardly-extending pins 120. Anchored to each pin is one end of a coil-spring 121, the opposite end of each spring being connected to one end of a short length of chain 122, each of which is secured at its opposite end respectively, to one of the pulleys 112. Each pin 120 also constitutes a post for supporting one end of a diametrical bar 123 which is adapted to be manually operated to rotate the pulley 117 about its axis 118. As shown in Fig. 4, the chain connections between the manually operated pulley 117 and the pulleys 112 are such that by rotating the pulley 117 in a counterclockwise direction, the shafts 109 and their respective frame-members 107, will rotate to bring the resilient wire-loops 115 of the latter into engagement with the elements of the work-piece. Although the pulley 117 is adapted to be rotated manually, it will be seen that the pulley 117 is also provided with a chain 124 secured at its upper end in a peripheral groove of the pulley 117, the lower end of the chain 124 being adapted to be secured to one end of a lever-arm 125 (see Fig. 1) pivoted to the underside of the support on which the sewing machine is mounted, the lever-arm 125 being one arm of a bell-crank lever having a foot-pedal (not shown) on the lower end of its other arm 126. Thus, by thrusting the lever-arm 126 rearwardly, the arm 125 will be pulled downwardly so as to rotate the pulley 117 in a counterclockwise direction and thus swing the work-piece retaining-members 115 into engagement with the elements of the work-piece.

In order to secure the work-piece-retaining wire-loops 115 in work-piece-engaging position, the pulley 117 is provided with locking-means comprising a transverse bar 127 on its periphery arranged to be operatively associated with a latch-member 128 which is pivotally mounted at its upper end to the stanchion 119. The latch-member 128 is provided at its upper end with a finger-piece 129 at substantially right angles to

its shank 130. The shank 130 is adapted to extend downwardly in a vertical plane substantially parallel to and in the plane of the inside face of the pulley 117, the lower end of the shank being provided with a forwardly-projecting finger 131 (see Fig. 1). Secured in the finger 131 is an adjustable screw 132, the latter being arranged to extend upwardly into the path of movement of the bar 127 of the pulley 117. The adjustable screw 132 is adapted normally to be held in the path of movement of the bar 127 by a coil-spring 133 which is secured at one end to the finger 131 and at its opposite end to a post 134 projecting from the underside of the work-holding plate. When the pulley is rotated to move the bar 127 into engagement with the upper end of the adjustable screw 132, the chain connections between the pulley 117 and the pulleys 112 will tension the spring 114. However, since engagement between the bar 127 and the adjustable screw 132 is effected below the dead center of the pulley 117, the bar 127 is resiliently held in engagement with the screw 132 by the force of the tensioned spring 114. In order to release the rotatable frame-members 107 and their work-piece-retaining wire-loops 115, the finger-piece 129 may be pressed down to pivot the latch 128 counterclockwise and swing the adjustable screw 132 out of engagement with the bar 127.

The operation of the sewing machine may be described briefly as follows. Assuming a sewing cycle has just been completed, the operator presses down on the finger-piece 129 of the ratchet-locking means 116 so as to release the pulley 117 and permit the work-piece-holding frame-members 107 to swing upwardly and outwardly away from the work-piece. Thereupon, the finished work-piece is removed from the work-piece-holding aperture 101 and the respective elements of a second work-piece are assembled on the ledge 105 thereof. The operator then thrusts rearwardly on the foot-pedal of the arm 126 of the bell-crank lever to pull the chain 124 downwardly and rotate the pulley 117 in a counterclockwise direction so as to engage the wire-loops 115 of the frame-members with the assembled elements of the work-piece, the adjustable screw 132 being adapted to engage the bar 127 of the pulley 117 to hold the work-piece-engaging members in locked position. Referring to Fig 3, the cord 81 of the second friction drive-band 77 is shown bent around a pulley 135 on the underside of the base and connected at its lower end to the bell-crank lever-arm 125. Consequently, when the lever-arm 126 is operated to actuate the work-piece-holding members, the second friction drive-band 77 will be simultaneously tightened around the disk 51 of the pinion-member 49 so as to rotate the latter in a clockwise direction, during which time the brake-band 69 is automatically released, as described above. The clockwise rotation of the pinion-member thus displaces the work-piece holder 88 and the work-piece with respect to the needle 11, the displacement of the work-piece being in a direction rearwardly of the position of the work-piece at the end of the previous sewing cycle. On releasing the pedal of the bell-crank lever-arm 126, the brake-band 69 again clamps around the pinion-disk 51 to prevent movement of the pinion-member, and thereafter the operator engages a second pedal not shown, but which is connected in any conventional manner to a pivoted starting-arm 136, the actuation of which positively forces the pivoted stop-lever

18 out of engagement with the lug 46 of the drive-pulley 14, whereupon the needle-shaft 12 and the oscillating shuttle shaft 46 begin to rotate. As the shuttle-shaft 46 oscillates, the drive-band 54 rotates the pinion-member intermittently in a counterclockwise direction, thereby transmitting intermittent motion to the rack plate 96. The latter being mounted for substantially-universal movement in a horizontal plane, moves in a path corresponding to the configuration of the cam-groove in the underside thereof, thus traversing a work-piece through a similar path, whereupon the needle 11 stitches a similar pattern around the periphery of the assembled elements of the work-piece. As the carriage and work-piece holder approach the end of the sewing cycle, the left-hand guide-rod 95 of the carriage engages and pushes the prop 33 of the latch-means 29 off of the edge of the base 27 of the machine, thereby automatically stopping the operation of the machine, as described above. Simultaneously, suitable means (not shown and not forming a part of the present invention) are actuated by the displaced stop-lever 48 to automatically release the thread. At the end of the sewing cycle, the final stitches sewn in the article have overrun the stitches initially sewn at the start of the sewing cycle, thereby effectively tying together the loose ends of the threads.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a sewing machine, the combination with a base; a carriage having a rack-plate; means to support said carriage on said base to permit universal movement of said carriage and rack-plate in a horizontal plane; a work-piece holder supported by said carriage; and drive-means for moving said carriage, said drive-means comprising an oscillating shuttle-shaft, a pinion-member arranged to cooperatively engage the rack-plate of said carriage, and a friction-drive band arranged to engage said pinion-member and to be actuated by said shuttle-shaft to transmit step-by-step rotary motion to said pinion-member.

2. In a sewing machine, the combination with a base; a carriage having a rack-plate; means to support said carriage on said base to permit universal movement of said carriage and rack-plate in a horizontal plane; a work-piece holder supported by said carriage; drive-means for moving said carriage, said drive-means comprising an oscillating shuttle-shaft, a pinion-member arranged to cooperatively engage the rack-plate of said carriage, and a friction-drive band arranged to engage said pinion-member and to be actuated by said shuttle-shaft to transmit step-by-step rotary motion to said pinion-member; and a brake-member arranged to frictionally engage said pinion-member to hold the latter stationary between successive steps.

3. In a sewing machine, the combination with a base; a carriage having a rack-plate; means to support said carriage on said base to permit universal movement of said carriage and rack-plate in a horizontal plane; a work-piece holder supported by said carriage; drive-means for

5 moving said carriage, said drive-means comprising an oscillating shuttle-shaft, a pinion-member arranged to cooperatively engage the rack of said carriage, and an element operatively associated with said shuttle-shaft arranged to transmit intermittent rotary motion to said pinion-member to move said work-piece holder through a sewing cycle; and stop-means arranged to be actuated by said carriage at the 10 end of said sewing cycle to automatically stop said drive-means.

4. In a sewing machine, the combination with a base; a carriage; means to support said carriage on said base to permit universal movement of said carriage in a horizontal plane; a work-piece holder supported by said carriage, said holder comprising clamping-members arranged to secure a work-piece to said holder; drive-means to move said universally-movable carriage through a sewing cycle; means to automatically stop said carriage at the end of said sewing cycle; carriage-resetting means; and operating-means connected to said clamping-members and said carriage-resetting means to 25 simultaneously clamp a work-piece in said holder and reset said carriage prior to the start of the next sewing cycle.

5. In a sewing machine, the combination with a base; a carriage having a rack-plate; means to support said carriage on said base to permit universal movement of said carriage and rack-plate in a horizontal plane; a work-piece holder supported by said carriage, said holder comprising clamping-members arranged to secure a 30 work-piece to said holder; drive-means arranged to move said carriage through a sewing cycle, said drive-means comprising a shuttle-shaft, a pinion-member arranged to cooperatively engage the rack-plate of said carriage, and an element 35 operatively associated with said shuttle-shaft arranged to transmit intermittent rotary motion to said pinion-member; and carriage-resetting means cooperatively associated with said pinion-member and arranged to be actuated simultaneously with the actuation of said work-piece 40 clamping-members to reverse the direction of rotation of said pinion-member at the end of said sewing cycle.

6. In a sewing machine, the combination with a base; a carriage having a rack-plate; means to support said carriage on said base to permit universal movement of said carriage and rack-plate in a horizontal plane; a work-piece holder supported by said carriage, said holder comprising clamping-members arranged to secure a work-piece to said holder; drive-means arranged to move said carriage through a sewing cycle, said drive-means comprising a shuttle-shaft, a pinion-member arranged to cooperatively engage the 55 rack-plate of said carriage, and a friction-drive band cooperatively associated with said shuttle-shaft arranged to transmit step-by-step rotary motion to said pinion-member; a brake-band arranged to engage said pinion-member to hold the latter stationary between successive steps; and a second friction-drive band in engagement with said pinion-member arranged to be actuated simultaneously with the actuation 60 of said work-piece clamping-members to reverse the direction of rotation of said pinion-member at the end of said sewing cycle to reset said carriage.

7. In a sewing machine, the combination with a base; a carriage having a rack-plate; means

to support said carriage on said base to permit universal movement of said carriage and rack-plate in a horizontal plane; a work-piece holder supported by said carriage, said holder comprising clamping-members arranged to secure a work-piece to said holder; drive-means arranged to move said carriage through a sewing cycle, said drive-means comprising a shuttle-shaft, a pinion-member arranged to cooperatively engage the rack-plate of said carriage, and a friction-drive band cooperatively associated with said shuttle-shaft arranged to transmit step-by-step rotary motion to said pinion-member; a brake-band arranged to engage said pinion-member to hold the latter stationary between successive steps; a second friction-drive band in engagement with said pinion-member arranged to be actuated simultaneously with the actuation of said work-piece clamping-members to reverse the direction of rotation of said pinion-member at the end of said sewing cycle to reset said carriage; and means arranged to automatically disengage said brake-band from said pinion-member when said second friction-drive band is operated to reverse the direction of rotation of said pinion-member.

8. In a sewing machine, the combination with a base; a carriage having a rack-plate; means to support said carriage on said base to permit universal movement of said carriage and rack-plate in a horizontal plane; a work-piece holder supported by said carriage, said holder comprising clamping-members arranged to secure a work-piece to said holder; drive-means arranged to move said carriage through a sewing cycle, said drive-means comprising a friction-drive band constructed and arranged to transmit step-by-step movement to said carriage; a brake-band cooperatively associated with said drive-means to hold said carriage stationary between successive steps; a second friction-drive band cooperatively associated with said drive-means to reverse the direction of movement of said carriage at the end of said sewing cycle; and operating-means connected to said clamping-members and said second friction-drive band to simultaneously clamp a work-piece to said holder and reset said carriage prior to the start of the next sewing cycle.

9. In a sewing machine, the combination with a base; a carriage having a rack-plate; means to support said carriage on said base to permit universal movement of said carriage and rack-plate in a horizontal plane; a work-piece holder supported by said carriage, said holder comprising clamping-members arranged to secure a work-piece to said holder; drive-means arranged to move said carriage through a sewing cycle, said drive-means comprising a friction-drive band constructed and arranged to transmit step-by-step movement to said carriage; a brake-band cooperatively associated with said drive-means to hold said carriage stationary between successive steps; a second friction-drive band cooperatively associated with said drive-means to reverse the direction of movement of said carriage at the end of said sewing cycle; operating-means connected to said clamping-members and said second friction-drive band to simultaneously clamp a work-piece to said holder and reset said carriage prior to the start of the next sewing cycle; and means arranged to automatically disassociate said brake-band from said drive-means when said second friction-drive band is operated to reset said carriage.

10. In a sewing machine, the combination with a base; a carriage; means to support said carriage on said base to permit universal movement of said carriage in a horizontal plane; a work-piece holder supported by said carriage; means to drive said carriage comprising a pinion-member arranged to transmit step-by-step movement to said carriage; carriage-resetting means comprising a friction-drive band in engagement with said pinion-member; and operating-means constructed and arranged to actuate said friction-drive band to reset said carriage at the end of the sewing cycle.

11. In a sewing machine, the combination with a base; a carriage; means to support said carriage on said base to permit universal movement of said carriage in a horizontal plane; a work-piece holder supported by said carriage; means to drive said carriage comprising a pinion-member arranged to transmit step-by-step movement to said carriage; carriage-resetting means comprising a friction-drive band in engagement with said pinion-member; a brake-band in engagement with said pinion-member; and operating-means constructed and arranged to simultaneously disengage said brake-band from said pinion-member and to actuate said friction-drive band to reset said carriage at the end of the sewing cycle.

12. In a sewing machine, the combination with a base; a carriage; means to support said carriage on said base to permit universal movement of said carriage in a horizontal plane; means to drive said carriage; a work-piece holder supported by said carriage, said holder having a recess to receive a work-piece; and work-piece clamping-means mounted on said holder, said clamping-means comprising a pair of frame-members hinged to said holder on opposite sides of said recess, each frame-member having resilient work-piece engaging elements arranged to automatically compensate for variations in thickness of said work-piece; and manually-operable means connected to said hinged-members and arranged to swing said hinged-members simultaneously into clamping-position whereby said resilient elements are adapted to clamp said work-piece in the recess of said holder.

13. In a sewing machine, the combination with a base; a carriage; means to support said carriage on said base to permit universal movement of said carriage in a horizontal plane; means to drive said carriage; a work-piece holder supported by said carriage, said holder having a recess to receive a work-piece; and work-piece clamping-means mounted on said holder, said clamping-means comprising a pair of frame-members hinged to said holder on opposite sides of said recess, each frame-member having resilient work-piece-engaging wire-loops arranged to automatically compensate for variations in the thickness of said work-piece; manually-operable means connected to said hinged members and arranged to swing said hinged members simultaneously into clamping-position whereby said wire-loops are adapted to clamp said work-piece in the recess of said holder; and ratchet-means to lock said hinged members in clamping-position.

14. In a sewing machine of the class described, a work-piece holder having work-piece clamping-means; intermittent drive-means for moving the work-piece holder through a sewing cycle and means operatively associated with said intermittent drive-means and actuated simultaneously with the actuation of the work-piece clamping-

15

means to reset the work-piece holder at the end of the sewing cycle.

15. In a sewing machine, the combination of a base-plate having a vertical aperture therein; a pair of spaced-parallel guide-rods; means arranged to support said guide-rods in a horizontal plane above the horizontal plane of said base-plate for longitudinal movement transversely to the longitudinal axis of said base-plate; a pair of spaced-parallel bearing-brackets secured to said guide-rods adjacent opposite ends thereof respectively, each bracket having a depending hanger provided with a bearing-aperture, the longitudinal axis of which extends substantially parallel to the longitudinal axis of the base-plate; a rack-plate; means to support said rack-plate in a horizontal plane immediately above the horizontal plane of said base-plate comprising a second pair of spaced-parallel guide-rods, each of said second pair of guide-rods being slidably supported in one of the said bearing-apertures of said brack-

10
